UNITED STATES PATENT OFFICE.

GEORGE W. KNAPP, OF BALTIMORE, MARYLAND.

PERFORATED PLATE FOR KITCHEN-SAFES.

SPECIFICATION forming part of Letters Patent No. 307,959, dated November 11, 1884.

Application filed July 3, 1884. (No model.)

To all whom it may concern:

Be it known that I, GEORGE W. KNAPP, a citizen of the United States, residing at Baltimore, in the State of Maryland, have invented certain new and useful Improvements in Perforated Plates for Kitchen-Safes, of which the following is a specification.

My invention relates to an improvement in perforated metal plates for kitchen-safes, and 10 will first be described and then claimed.

The invention is illustrated in the accompanying drawings, in which Figure 1 is a view of an ordinary kitchen-safe having the improved perforated plates attached. Fig. 2 15 is a view showing the metal plate in the first stage of preparation with the ornamental design printed therein in colors. Fig. 3 is a view showing the finished metal plate—that is, with the ornamental design thereon in colors and 20 perforated.

Heretofore perforated tin plates for kitchen-safes have been punched so as to produce a burr projecting on one surface of the plate. The surface having the projecting burrs 25 constitutes the outer surface, and the plate is secured to the safe with said burred surface out. It will be understood that the perforations serve to ventilate, while the outward-projecting burr about each perforation serves to prevent 30 insects from passing into the safe. These perforations also have been so arranged and disposed as to produce the outlines of figures or designs of a crudely-ornamental character.

The object of my invention is to ornament 35 the outer surface of these plates with colored designs, so applied as to avoid obstructing the perforations, and to be protected from defacement by the projecting burrs.

I pursue the following method in producing 40 the improved plate. The plate A, generally of tin, is first painted or printed on one side, in one or more colors, with some ornamental figure or design, as shown in Fig. 2. It is immaterial what the particular design may be, 45 and the same may be anything that taste or fancy suggests. The design having been determined on, the same is painted or printed on the tin plate by any suitable or known means.

A perforating-die is made of the usual kind used in stamping these plates, which will so dispose or locate the perforations b in the tin plate as will produce in a general way a similar design to that determined on, or that will complement or correspond with the said design in colors, the purpose or intention being that the shapes or parts of the design in colors and the shapes or parts of the design in perforations shall supplement each other. In other words, my aim is to produce the decorative and ornamental effect by the design in 50 colors, and then to locate the ventilating-perforations with respect to the features of the said colored design so that the beauty of the latter will not be marred or impaired thereby. The plates having had the design in colors applied and dried, are then perforated by the die referred to, or by other means, the burrs projecting on the surface which has the design. By this method a handsome perforated plate 55 may be produced at little cost, and the ornamental design in colors will be protected from defacement by the projecting burrs, while the ventilating-perforations will not be obstructed.

Having described my invention, I claim and desire to secure by Letters Patent of the United States—

1. The method of ornamenting perforated plates for safes, consisting in first applying a colored design to a surface of the plate, and then making the ventilating-perforations with 60 respect to the features of the said colored design, and producing on the same surface a burr projecting about each perforation, as set forth.

2. A ventilating-plate for safes, having an 65 ornamental colored design on one surface, and ventilating-perforations with burrs projecting on the same surface, and so located as to avoid marring the said colored design, as set forth.

In testimony whereof I affix my signature in 70 presence of two witnesses.

GEORGE W. KNAPP.
